UNITED STATES PATENT OFFICE.

JAMES FISK, OF BRATTLEBOROUGH, VERMONT.

HORSE-DETACHER.

SPECIFICATION forming part of Letters Patent No. 234,664, dated November 23, 1880.

Application filed October 1, 1880. (No model.)

To all whom it may concern:

Be it known that I, JAMES FISK, of Brattleborough, in the county of Windham and State of Vermont, have invented an Improvement 5 in Detaching Traces from Whiffletrees, of which the following is a specification.

I provide on the whiffletree a box containing two gears, and these are operated by a sliding rack, and there are bolts with toothed 10 racks that are made use of to force outwardly spring-shackles that hold the traces, and in so doing disconnect the traces from the pins at the ends of the whiffletree.

In the drawings, Figure 1 is an inverted 15 plan, partially in section, of the detaching device, and Fig. 2 is a front view of the spring-shackle.

At each end of the whiffletree *a* there is a straight pin, *b*, that is adapted to receive over 20 it the eye of the trace.

The shackle is made with an eye, *c*, that slides upon the pin *b*, a bolt, *d*, that enters the case *e*, and an outer holding-arm, *h*, having a recess for the end of the pin *b*.

25 Within the case *e* there is an expansive helical spring, *l*, acting against the head of the bolt *d*, to draw the same along and hold the arm *h* firmly against the end of the pin *b*.

When the eye of the trace is to be slipped 30 over the pin *b*, the arm *h* is grasped and pulled away from *b* against the action of the spring

l, to give opportunity to slip the eye of the trace over the pin.

At the center of the whiffletree there is a box, *m*, having within it the two gears *n n*, 35 that act against the teeth on the rack-bar ends of the bolts *o o*, and there is a rack, *r*, that is between the two gears and slides endwise across below the rack-bolts, and to this a rack-chain is attached, that passes to the body of 40 the vehicle, where it is connected with a lever, by means of which the detaching apparatus is operated. When this chain is pulled the rack *r* is moved endwise, both gears *n n* are partially revolved, and the rack-bolts are 45 pushed outwardly, and their ends, which rest against the bolts *d*, moving them and the shackles endwise of the pins *b* and the traces, are forced off the said pins *b* by the eyes *c*, and the horse liberated. 50

This improvement may be duplicated for a team of horses.

I claim as my invention—

The box *m*, gears *n n*, rack bars and bolts *o*, and cross sliding rack *r*, in combination 55 with the spring-bolts *d*, shackles *c h*, and pins *b*, substantially as set forth.

Signed by me this 24th day of September, A. D. 1880.
